(57) **CLAIM**

I claim the ornamental design for a putter, as shown and described.

DESCRIPTION

FIG. 1 is a perspective view of a putter showing my new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a bottom plan view thereof;

FIG. 6 is a top plan view thereof;

FIG. 7 is a perspective view of a putter shown in an alternate configuration;

FIG. 8 is a front elevational view thereof;

FIG. 9 is a rear elevational view thereof;

FIG. 10 is a right-side elevational view thereof, the left-side elevational view being a mirror image thereof;

FIG. 11 is a bottom plan view thereof; and,

FIG. 12 is a top plan view thereof.

The broken lines showing a putter shaft in FIGS. 1 and 7 depict environmental matter and form no part of the claimed design.
